Primary Examiner — Adir Aronovich(74) *Attorney, Agent, or Firm* — Haynes and Boone, LLP(57) **CLAIM**

The ornamental design for a sensor housing, as shown and described.

DESCRIPTION

FIG. 1 is a front left top perspective view of a sensor housing showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depict the portions of a sensor housing in which the design is embodied and form no part of the claimed design.
